UNITED STATES PATENT OFFICE.

BYRON BENJAMIN GOLDSMITH, OF NEW YORK, N. Y.

DESIGN FOR A LEAD-PENCIL.

SPECIFICATION forming part of Design No. 22,511, dated June 6, 1893.

Application filed February 17, 1893. Serial No. 462,776. Term of patent 7 years.

To all whom it may concern:

Be it known that I, BYRON BENJAMIN GOLDSMITH, a citizen of the United States, and a resident of New York, in the county and State of New York, have invented and produced a new and original Design for Lead-Pencils, of which the following is a specification.

Figure 1, represents a cross-section, and Fig. 2, a perspective view of a lead pencil showing my design.

The leading feature of my design consists in the generally triangular form of the mantle of the lead pencil, the triangle being equilateral, but the sides, instead of being straight, are formed with obtuse re-entering angles, so that the cross-section of the lead-pencil presents a figure which is inscribed in an equilateral triangle.

In the drawings, the three projecting edges of 1, 1, 1, of the mantle, are shown as formed by

the intersection of the sides 2, 2, of the re-entering angles 3, 3, 3, and the latter again are formed by the intersections of the projecting edges 1, 1, 1. In this manner there are produced six flat faces, variously inclined toward each other, but which at the same time are grouped about the lead or graphite 4, in a symmetrical order or sequence, by which a new aesthetic effect is produced.

What I claim is—

The design for a lead pencil, substantially as herein shown and described.

In testimony whereof I have signed my name to this specification in the presence of two subscribing witnesses.

BYRON BENJAMIN GOLDSMITH.
